UNITED STATES PATENT OFFICE.

LUKE CHAPMAN, OF COLLINSVILLE, CONNECTICUT, ASSIGNOR TO THE
COLLINS COMPANY, OF SAME PLACE.

MANUFACTURE OF WRENCH-FORGINGS.

SPECIFICATION forming part of Letters Patent No. 300,445, dated June 17, 1884.

Application filed April 22, 1882. Renewed October 29, 1883. (No model.)

To all whom it may concern:

Be it known that I, LUKE CHAPMAN, of
Collinsville, in the county of Hartford and
State of Connecticut, have invented certain
new and useful Improvements Pertaining to
the Manufacture of Wrench-Forgings, of
which the following is a specification, refer-
ence being had to the accompanying drawings,
in which—

10 Figure 1 shows a side view of a bar-section
(of iron or steel) such as commercial bars are
cut into as a step preparatory to the other
steps taken in carrying out this invention.
Fig. 2 shows an edge view of the same bar-
15 section. Fig. 3 shows a side view of the same
bar-section after its division, by suitable dies
or spears, into two corresponding blanks.
Fig. 4 shows a face view of the heading-die.
Fig. 5 shows a side view of the heading-die.
20 Figs. 6 and 7 show face views of the corre-
sponding parts of the holding-die. One of
these parts is represented as holding one of
the blanks shown in Fig. 3, preparatory to
the heading operation. Figs. 8 and 9 show
25 upper end views of the corresponding parts
of the holding-die, as in Fig. 6 the blank is
shown in one of the parts. Fig. 10 shows a
view of the forging produced by the heading
operation.

30 This invention is herein shown and described
as applied to the production of a forging for
the bar and head of a "hammer" or "monkey"
wrench. These forgings were originally pro-
duced by the common blacksmith's art. Since
35 then various methods and means have been
tried to abridge and cheapen their manufac-
ture.

An advantage of the methods and means
herein described is that one is enabled to take
40 commercial bars—that is, bars of iron or steel
such as are readily procurable in market with-
out extra cost for peculiarity of shape—and by
short and simple and cheap operations con-
vert them into the desired forgings.

45 This method and means are as follows: Take
commercial bars, substantially rectangular in
cross-section with greater width than thick-
ness, and cut them—cold or hot, but prefera-

bly cold—into the lengths or bar-sections *a*.
Then by suitable cutting-dies or shears cut 50
these bar-sections—cold or hot, but prefer-
ably cold—into the two corresponding blanks
b. Then heat the large end of the blank to a
forging-heat and place it in the holding-die.
This holding-die has a "head-matrix" for 55
forming the head and a bar-matrix for hold-
ing the bar. It is preferably made in two cor-
responding halves or parts, *c c*, which, in suit-
able machinery and under suitable power,
close together face to face to hold the blank 60
during the heading operation, and then open
again. After the blank is in place in the
holding-die, the heading-die *d*, moved by suit-
able machinery and under suitable power, ad-
vances toward the holding-die, upsetting the 65
enlarged end of the blank, and forcing the
metal thereof to fill the head-matrix of the
holding-die, after which the heading-die re-
treats to its normal position of rest. Practi-
cally the amount of stock in the enlarged end 70
of the blank should be slightly in excess of
the amount required for the head of the for-
ging, in order to insure the complete and en-
tire filling of the head-matrix. This excess
will form a fin, *e*, on the forging, which is 75
afterward trimmed off.

The essential feature of the blank *b* is that
the enlargement at one end is substantially on
one side of the bar, and that it has underneath
the shoulder *b' b'*, which, by resting upon the 80
bottom of the head-matrix, substantially aids
in supporting the blank under the heading
operation.

The characteristic feature of the dies is that
the walls of the head-matrix form the bottom, 85
sides, and end or ends of the head, while the
heading-die does not enter the holding-die,
but overlaps the head-matrix, and in action
forces the excess of metal into lateral fin or
fins.

A substantial part of this invention is used
if the cutting of the bar-section into the cor-
responding blanks *b b* is omitted and blanks
of this shape be otherwise produced.

To give an idea of the dimensions of the 95
commercial bars used and of the blanks and

dies, I have in some of the accompanying drawings given in figures the dimensions for a fifteen-inch wrench. Dimensions for other sizes can be readily gotten at from these.

5 I claim as my invention—

The method, art, or process of producing wrench-forgings, consisting in cutting bar-sec-

tions *a* into the blanks *b b*, and then heading the blanks in dies, all substantially as herein described.

LUKE CHAPMAN.
